UNITED STATES PATENT OFFICE.

ROBERT HOFFMAN, OF PITTSBURG, PENNSYLVANIA, ASSIGNOR TO THE
H. J. HEINZ COMPANY, OF SAME PLACE.

BUNG FOR PICKLE-BARRELS.

SPECIFICATION forming part of Letters Patent No. 429,448, dated June 3, 1890.

Application filed September 27, 1889. Serial No. 325,315. (No model.)

To all whom it may concern:

Be it known that I, ROBERT HOFFMAN, of Pittsburgh, in the county of Allegheny and State of Pennsylvania, have invented a new 5 and useful Improvement in Barrel-Bungs, of which the following is a full, clear, and exact description.

I shall describe my improvement with reference to the accompanying drawings, in 10 which—

Figure 1 is a top plan view of a barrel provided with my improved bung. Fig. 2 is a vertical irregular section on the line II II of Fig. 1.

15 Like figures of reference indicate like parts in each.

The object of my invention is to provide a 20 bung for the head of a pickle-barrel and the like which shall be secure in its action in closing the barrel, easy to remove and replace, neat and attractive in appearance, and cleanly 25 in preventing the accumulation of dirt and vermin. The bung described in this specification possesses these advantages and the 30 further advantage that the barrel or package 35 may be preserved for holding its contents in retail stores, the use of the bung making it unnecessary to injure the barrel in getting access to its contents. The usual practice of 30 breaking the barrel-head to open the barrel 40 possesses so many disadvantages that the benefits of my improved bung in this regard will be very much appreciated.

Referring to the drawings, 2 represents the 45 barrel, having in its head a hole to permit the insertion and removal of its contents without making it necessary to remove the entire barrel-head. 3 is the bung which I employ to close this hole. It consists of a metal plate 50 or disk having on its surface a suitable ring or handle 7, by which it may be removed from the hole and replaced thereon for use as a cover. The bung-disk 3 has on its under side a circular flange 12, preferably tapering in 55 form. The disk projects laterally somewhat around the circumference of this flange, and is provided with laterally-projecting arms or lugs 4 and 8, the lug 4 having a screw-hole formed therein. The lugs 8 are preferably 60 formed with longitudinal surface ribs, as

shown in Fig. 1. There may be any suitable number of such lugs employed.

5 is a rubber gasket, which encircles the flange at the junction thereof with the disk.

I make the arms or lugs 8 of some length 55 and apply to the barrel-head catches 9, consisting of horizontally-projecting arms secured by base-plates to the barrel-head. The under sides of these arms are somewhat separated from the barrel-head and are made of 60 inclined form. The catches are preferably situated about diametrically opposite to each other relatively to the center of the bung-hole and are oppositely directed.

In using this fastening device I apply the 65 bung to the barrel and then impart to it a partial revolution, so as to bring the arms from the positions shown in dotted lines in Fig. 1 to those shown in full lines therein.

The effect of this is to bring the lugs beneath 70 the catches, and the inclination of the bases of the latter exerts a wedge action on the lugs and forces the bung downwardly, so as to compress the gasket. When the bung is thus applied, it may be secured by a screw inserted 75 through the hole in the lug 4 or otherwise. The bung may be further secured to the barrel-head by a hinge-connection, so that when the bung is loosened from its pressure on the gasket it may be raised up from the bung- 80 hole without entirely detaching it from the barrel-head. Such a hinge is shown in the drawings. It comprises a lug 10, projecting from the plate and provided with an elongated slot. A hooked plate 11 is fixed to the 85 barrel-head and fits in the slot, so as to permit the bung to be lifted on the hinge and thrown back on the barrel-head without preventing the rotation of the bung in the act of compressing the bung on its seat with the projecting arms and inclined catches. The construction of the hinge is such that the bung 90 may easily be detached by unscrewing the hooked plate and removing the bung and plate from the barrel-head.

95 The advantages of my invention have been generally indicated in the foregoing specification. The bung may be made very neat and ornamental in appearance by constructing it of cast-iron (malleable castings are preferable) 100

and coating the exterior thereof with vitreous enamel of any suitable color or pattern.

I claim as my invention—

The combination, with a barrel, of a bung or cover consisting of a plate or cap having a circular downwardly-projecting portion adapted to enter a hole in the barrel and a marginal flange adapted to fit on the outer surface of the barrel, arms projecting horizontally from the marginal flange, catches secured to the surface of the barrel and having inclined bearing-faces adapted to engage the

arms and to force the bung to its seat when said bung is rotated, and a gasket encircling said downwardly-projecting portion, substantially as and for the purposes described. 15

In testimony whereof I have hereunto set my hand this 23d day of September, A. D. 1889.

ROBERT HOFFMAN.
